CLAIM

The ornamental design of a ventilated waste can with frusto-conical lid, as shown and described.

DESCRIPTION

FIG. 1 is a front perspective view of the ventilated waste can with frusto-conical lid according to the inventive design; FIG. 2 is a front elevation view, the rear being substantially the same;

FIG. 3 is a side elevation view, the opposite side being substantially a mirror image;

FIG. 4 is a top plan view; and,

FIG. 5 is a bottom plan view.
